No. 1.
Nicholas Muller's Design for Seats of Best Cover Cloth.

Patented July 1, 1856.

No. 812.

Des. 812

Nicholas Muller
of New York N. Y.
Letters Patent No. 812, Dated July 1, 1856

The schedule referred to in these Letters Patent and making full disclosure:

To all whom it may concern:

Be it known, that I, Nicholas Muller, of the City, County, and State of New York have invented a new and original Design for the base of clock case fronts; and I do hereby declare that the following is a full, clear and exact description of the same, reference being had to the accompanying drawings, forming a part of this specification, in which

Fig. 1, is a front view of the base of a clock case front showing the design.

Fig. 2, is a side view of the same.

Fig. 3, is a sectional profile view in the line 2.2. - Similar letters of reference indicate corresponding parts in the several figures.

The general character of this design is a Hunter. -

A, is the base of the clock case front, in its outline it is of the form shown in Fig. 1, and consists of a combination of tree stumps B, B, B², roots C, C, C, leaf foliage D, D, and blades of grass E, E, arranged, in the relation to each other shown, on the base of the case front so as to stand out in relief and present a tasteful and ornamental appearance as shown in Figs 1, 2, and 3. - The stump B² which forms the central or main part of the base A, has the hole F, through which the pendulum is exposed and regulated from

ed in it as represented.-

On the right side of the hole H , a male figure G , draped and equipped as a Hunter, reclines upon the stump B^2 in the manner represented. And on the left of said hole is the figure of a dog H , which is sitting on its hind legs, as represented.-

The two figures stand out in relief from the blades of grape, and are also formed on the base of the case front in relief, as will be seen by referring to Figs 1, 2, and 3.

What I claim as my invention and desire to secure by Letters Patent, is

The male figure G , dog H , stumps B, B, B^2 , roots C, C, C , leaf foliage D , and blades of grape E , when arranged and combined as shown to form an ornamental design for a clock case front.-
